FIG. 4

Inventor,

Aaron S. Nichols,

By his Attorney,

W. B. Hutchinson,

UNITED STATES PATENT OFFICE.

AARON S. NICHOLS, OF NEW YORK, N. Y.

LUMBER-DRIER.

1,318,794.

Specification of Letters Patent. Patented Oct. 14, 1919.

Application filed October 9, 1918. Serial No. 257,505.

To all whom it may concern:

Be it known that I, AARON S. NICHOLS, a citizen of the United States, and a resident of the city, county, and State of New York, 5 have invented a new and useful Improvement in Lumber-Driers, of which the following is a full, clear, and exact description.

My invention relates to improvements in lumber driers, and more particularly to improvements in lumber driers of the platen type, in which a series of superposed platens are used, each platen being supplied with a heating medium, and the platens adapted to be separated to receive the lumber between them. The object of my invention is to improve driers of this type so that dimension stuff, that is lumber of different lengths and sizes, can be more conveniently placed in them or removed from them, to 10 economize heat by providing means for applying the heat more directly to the points where it is needed, to make all parts of the drier more accessible, and to provide expandible or swinging joints at the platen ends which will be simpler, more durable, and less wasteful of heat than in driers of this type heretofore used. The invention is also intended to provide means for a wider range of temperatures, that is to say, in drying lumber it is sometimes necessary to use a 15 comparatively low temperature for a certain period and then apply a higher temperature, and my invention is intended to make this result easily obtainable. A further advantage in this arrangement is that with driers of the ordinary kind where a high temperature is had and a lower one is desirable, the thermostats which usually control this apparatus do not respond quickly enough to 20 provide for the necessary changes. All of which will be more clearly understood from the description which follows.

Reference is to be had to the accompanying drawings forming a part of this specification, in which similar reference characters indicate corresponding parts in all the views.

Figure 1 is a side elevation of a drier embodying my invention showing the platens closed.

Fig. 2 is a similar view with the platens separated.

Fig. 3 is a plan view of a form of platen which lends itself readily to my improvements, and

Fig. 4 is an end view of the drier.

In the drawings I have shown so much of

the drier as is necessary to illustrate clearly the application of my invention. The drier has a base 10 of suitable design, a top frame 11, and rams 12 for raising and lowering the top and separating and closing the platens 13. This mechanism is not shown in detail, and is only illustrated in a general way to make clear the application of the improvements. Each platen 13 is suitably arranged for carrying a steam coil 14 which has an inlet 15 at one corner and an exhaust 15^a at the opposite end and other side. The coils of the platens are supplied with a heating medium, usually steam, at opposite ends of the drier, the heating medium coming in through inlet pipes 16 and 17 which are provided with valves 18. In practice these valves can obviously be located at a distance from the drier or in any convenient place to control the steam inlet. There is a bank of other connecting pipes 21 at each end of the drier and on opposite sides, one side being for the inlet and the other for the exhaust. For instance, as shown in Figs. 1 and 2 the inlet pipe 16 connects by means of a short pipe 19 and flexible joint 20 with a short pipe 21, and this has a flexible joint or swing joint 22 connecting with the coil 14 of one of the platens 13, while on the right hand side the lower pipe 21 of the bank of pipes connects with the second platen, that is the one next above the first, and so on. These joints can be any suitable flexible or swing joint, and it will be noticed that on one end the pipes connect with the coils 14 of the odd platens, that is 1, 3, 5, 7, etc., while on the other end the pipes connect with the even platens 2, 4, 6, 8, etc. It will be noticed that the pipes 21 can be short so as to have a small radiating surface, and as the pipes are connected by swing or flexible joints the platens can be raised or lowered without straining either pipes or joints. This is important as will be explained presently. Each pipe 16 and 17 also connects by the pipes 23 with the topmost pipe 21, the pipes 23 being connected by a flexible joint 24 and connecting with the inlet pipes and the upper pipes 21 by flexible joints 25. In Fig. 4 I have shown the pipe connections on one side only of the drier, as the arrangement is just the same on the other and there is no need of duplication.

Attention is called to this arrangement of pipes which has the following advantages. First, as constructed in many driers of this

type, long banks of pipes are arranged on the sides of the driers, and the spring of the pipes is depended on largely to allow the movement of the platens. The disadvantage 5 of this arrangement is, first that the banks of long pipes form a large radiating surface from which the heat is practically lost, as it is thrown off from the sides of the drier without doing any good work. Second, the 10 constant movement of the platens causes the pipes to weaken at the joints so that ultimately they break off. Then again by having the pipes 23 extend to the top of the banks of short pipes I get a simultaneous 15 and even application of steam to all parts of the drier, as the steam flows in from the bottom as well as the top, and thus an even pressure is quickly established in all parts of the drier. Furthermore, by the arrangement 20 of the short flexible pipes the end portions and the greater part of the sides of the drier are left open so that the drier can be filled or unloaded at both the ends and sides, whereas with the long bank of substantially rigid pipes generally used only 25 long lumber can be dried, and this has to be introduced or taken from the ends of the drier.

It will be understood, of course, that in 30 practice the drier can be cased in by any usual or preferred form of casing, and the exhaust comes through the bank of pipes on the opposite side from the inlet.

Another important advantage of the arrangement shown, and especially of having the bank of flexible pipes connect with one set of platens at one end of the machine, and the other bank at the opposite end connect with the intervening platens, is this; if the 35 temperature is too high, when steam or other heating medium is applied to all the platens, it can be shut off from half of them in my arrangement, thus leaving every other platen hot, and of course the temperature 40 will be comparatively low, and on the other hand the steam can be instantly turned on to all the platens, thus raising the temperature to the desired point.

In the drawings I have shown how the 50 upper ends of the pipe banks can be supported by hangers 26, but any suitable means for supporting them can be used.

I wish it clearly understood that in this 55 application the construction of the drier as a whole is not gone into in detail, and is not claimed, but the invention lies in the arrangement of the inlet pipes, the flexible construction of the several banks of pipes, the individual control of the inlet to the 60 platens, and the construction and arrangement of the flexible pipes generally.

I claim:

1. In a platen type of lumber drier having horizontally arranged platens carrying heating coils, the combination with such platens, 65

of banks of pipes, and connecting by flexible joints with the coils of the platens.

2. In a lumber drier of the type employing spaced platens movable up and down carrying heating coils, the combination with 70 such platens, of banks of pipes at the sides of the drier, said pipes being connected together by flexible joints and connected also to the coils of the platens.

3. In a lumber drier having horizontally 75 arranged platens carrying heating coils, the platens being movable up and down, the combination with such platens, of pipes at the sides of the drier connected together by flexible joints and to the coils of the platens, 80 and means for admitting a heating medium at the upper and lower parts of said banks of pipes.

4. In a lumber drier of the kind described, the combination with the horizontally arranged 85 platens having heating coils, of banks of pipes connected together with flexible joints and connected with the coils of the platens, and means for cutting out or in the heating medium from part of the 90 platen coils without disturbing the connections with the remaining platen coils.

5. In a drier of the kind described, the combination with the platens carrying heating coils, said platens being arranged horizontally one above the other and movable 95 up and down, of short banks of pipes connected by flexible joints and arranged to produce a lazy-tongs effect, said banks being located near the ends and on the sides of the drier, the banks of pipes at one end connecting with every other platen, and the banks at the other end connecting with the intervening platens.

6. In a drier of the type described having 105 horizontally arranged platens carrying heating coils, the combination with such platens, of banks of pipes having flexible joints arranged near the end portions and at the sides of the drier, the banks of pipes at one end 110 connecting with a portion of the platens and at the other end with the remaining platens, and an individual control for the inlet of the separate banks of pipes.

7. The combination with the movable 115 platens carrying heating coils, of separate banks of pipes having flexible joint connections with each other, and the banks being arranged opposite different portions of the platens, the banks at one end connecting 120 with certain of the platens and the banks at the other end connecting with the remaining platens, separate valve controlled inlet pipes for the two banks of pipes, and a flexible connection between the inlet pipe and the 125 lower end of a bank of pipes and also with the upper end of said bank of pipes, whereby quick and even pressure is supplied to the several pipe banks and platens.

8. The combination with the movable 130

horizontally arranged platens carrying heating coils, of a bank of inlet pipes opposite the platens, said pipes being arranged in and connected together by flexible joints, and also connected to a portion of the platens but not to all.

9. The combination with the movable horizontally arranged platens carrying heating coils, of banks of short pipes connected by flexible joints and arranged at the sides

of the drier and near opposite end portions of the platens whereby the sides of the drier are left open, connections between the pipe banks and the coils of the platens, and steam connections for the pipe banks.

AARON S. NICHOLS.
